(57) **CLAIM**

The ornamental design for a light fixture, as shown and described.

DESCRIPTION

FIG. 1 is a bottom perspective view of a light fixture showing our new design;

FIG. 2 is an alternate bottom perspective view thereof;

FIG. 3 is a top perspective view thereof;

FIG. 4 is a bottom view thereof;

FIG. 5 is a top view thereof;

FIG. 6 is a front view thereof, wherein the rear view, right side view and left side view are mirror images and identical thereto; and,

FIG. 7 is a cross-sectional view at 7-7 in FIG. 3 thereof. The broken lines showing the remainder of the light fixture are for environmental purposes only and form no part of the claimed design.
